UNITED STATES PATENT OFFICE.

ROY FISHER, OF PASADENA, CALIFORNIA.

DESIGN FOR A TRAFFIC SIGNAL.

Application filed September 8, 1927. Serial No. 23,325. Term of patent 14 years.

To all whom it may concern:

Be it known that I, Roy Fisher, a citizen of the United States, residing at Pasadena, in the county of Los Angeles and State of California, have invented a new, original, and ornamental Design for a Traffic Signal, of which the following is a specification, reference being had to the accompanying drawing, forming part thereof.

Figure 1 is a front elevation of a traffic signal, showing my new design.

Figure 2 is a rear view, and Figure 3 is a perspective view the same showing the bracket arm which is omitted in Fig. 1 and partially shown in Fig. 2.

I claim:

The ornamental design for a traffic signal as shown.

ROY FISHER.
